CLIP BROOCH

Jules Hirsch, New York, N. Y., assignor to Du Jay,
Inc., a corporation of New York

Application June 15, 1937, Serial No. 148,331

9 Claims. (Cl. 63—20)

This invention relates to a clip brooch; and has for one of its objects the provision of a pair of clips and a supporting frame so arranged that the clips may be more easily positioned on the supporting frame than in constructions in which it is necessary to thread one jaw of the clip through some opening in the frame.

Another object of the invention is the formation of a frame with clips so that they may be positioned on the frame by spreading the jaws of the clip open but a short distance.

Another object of the invention is the secure holding of the clips on the frame after being assembled thereon.

Another object of the invention is the provision of an arrangement so that the frame is contacted or engaged by both jaws of the clip so that the clips are held firmly in position on the frame.

Another object of the invention is the formation of a snap fastening arrangement between one of the jaws of the clip and the frame to hold the clips in position.

Another object of the invention is the provision of a single snap fastening means which will hold the clips in position without the clips rotating about the snap fastening means.

Another object of the invention is the formation of a resilient back jaw with engaging arms having no free ends and with the resiliency distributed throughout the back jaw for holding the back jaw of the frame in position upon a stud which is raised from the frame.

With these and other objects in view, the invention consists of certain novel features of construction, as will be more fully described, and particularly pointed out in the appended claims.

In the accompanying drawing:

Fig. 1 is a top plan view of the clip brooch in assembled position;

Fig. 2 is a rear view of the assembly on a much larger scale;

Fig. 3 is a sectional view on line 3—3 of Fig. 2;

Fig. 4 is a bottom plan view of the frame alone;

Fig. 5 is a bottom or rear plan view of the clip alone;

Fig. 6 is a sectional view on line 6—6 of Fig. 5;

Fig. 7 is a sectional view on line 7—7 of Fig. 4;

Fig. 8 is a perspective view of the mounting member for the front jaw or ornament of the clip.

It is desirable in costume jewelry to provide an assemblage of different ornaments such for instance as a pair of clips which may be individually worn or an assemblage of these individual ornaments upon some frame or supporting struc-

ture to provide a brooch whereby both the ornaments may be worn as a single unit, and various ways have been devised for accomplishing this general result. I have improved the arrangement so that the clips may be more easily held in position than heretofore; and the following is a more detailed description of the present embodiment of this invention, illustrating the preferred means by which these advantageous results may be accomplished:

With reference to the drawing, 10 designates generally the supporting frame which has mounted lengthwise thereof a pin shank 11 hinged as at 12 and provided with a safety catch 13 for holding the same in clasped position. The frame 10 is cut out as at 14 with a slot 15 open at its end 16 and providing spaced portions 17 extending laterally of the lengthwise extent of the frame. The longitudinally extending portions 18 of the frame have raised studs 19 which are of extended length 20 and are straight as at 20 along their side edges, being indented as at 21 to provide a head portion 22, as may perhaps best be seen in the sectional view shown in Fig. 7, the side wall of the stud being arcuate to receive a correspondingly shaped 25 projection on a spring gripping arm.

The pair of clips are substantially identical each comprising a back jaw shaped as shown in Fig. 5, and being somewhat of a skeleton framework structure by reason of the openings 22, 23, 24 and 30 25 within its periphery. This skeleton work structure is so arranged, however, as to provide a pair of arms 26 with a space 27 between them, with inwardly extending arcuate portions 28 which are so arranged as to receive and snap over the head 22 35 35 of the stud 19 and fit the arcuate concavities along the side, such snapping action occurring by reason of the arms 26 as well as the peripheral portions 29 of the jaws expanding or spreading outwardly.

This back jaw is hingedly related to a mounting member 30, shown in perspective in Fig. 8, and comprising a plate portion 31 with a pair of ears 32 having openings 33 for pivotally receiving the trunnions 34 which project laterally from the back jaw, this back jaw being rolled as at 35 between these ears and provided with a projection 36 to engage the spring 37 at one side of the pivotal axis so as to receive a thrust from the spring tending to force the back jaw in a direction around its pivot toward closing position during a certain angular relation with reference to such closed position. A flange 38 is provided on the edge of the plate 31 to assist in holding the spring in position, while fingers 39 are cut from the plate and bent upwardly to a height equivalent to the bent- 55 55

up edge of the lip 40, the fingers 39 serving to assist in locating the spring 37 which is positioned between these fingers and the flange 38, and also serving as a locating point for the portions 17 of the frame when positioned as shown in Fig. 3.

The portion 17 presents an edge 41 which engages the ears 32 of the clip, while the fingers 39 and lip 40 engage the front side of the frame so as to definitely locate this frame and clip in position, whereupon the closing of the jaw to the position such as shown in Figs. 2 and 3, locates the back jaw along the back surface of the frame so that the frame may be well supported between the ends of the fingers 39 and edge of the lip 40 on one side and the back jaw on the other side of the frame. Also, the opening 27 extends over the stud 19 and the resilient arms grip this stud beneath its head 22 as shown in Fig. 7 to hold the clip firmly in position. The elongated stud 20 as well as the engagement of both ears 32 prevent a lateral swinging movement of the clip on the frame.

The mounting portion or plate 31 of the clip has an ornament 42 soldered thereon as at 43 so that this ornament provides the other jaw of the clip. Suitable spurs 44 are also provided on the back jaw for gripping fabric or the like, but serve no particular function in the mounting of the clip on the frame.

30 The foregoing description is directed solely towards the construction illustrated, but I desire it to be understood that I reserve the privilege of resorting to all the mechanical changes to which the device is susceptible, the invention 35 being defined and limited only by the terms of the appended claims.

I claim:

1. In a clip brooch, a supporting frame, means 40 for attaching the same to a garment, said frame having spaced laterally extending portions leaving a space between them for lateral entrance, a clip having a pair of jaws movable laterally into said space to position its jaws over one of said portions whereby closing the jaws grips the 45 said portion between said jaws.

2. In a clip brooch, a supporting frame, means 50 for attaching the same to a garment, said frame having spaced laterally extending portions leaving a space between them for lateral entrance, a clip having a pair of jaws movable laterally into said space to position its jaws over one of said portions whereby closing the jaws grips the 55 said portion between said jaws, and snap fastening means carried by one of said jaws and said frame to hold the clip and frame in assembled relation.

3. In a clip brooch, a supporting frame, means 60 for attaching the same to a garment, a clip having front and back jaws with one jaw positioned on one side and the other jaw positioned on the other side of a portion of said frame, snap fastening means between said frame and back jaw to hold the clip and frame assembled comprising a stud on said frame, and a pair of resilient arms 65 on said back jaw to grip said stud.

4. In a clip brooch, a supporting frame, means 70 for attaching the same to a garment, a clip having front and back jaws with one jaw posi-

tioned on one side and the other jaw positioned on the other side of a portion of said frame, snap fastening means between said frame and back jaw to hold the clip and frame assembled comprising an integral stud raised from the stock 75 of said frame, and a pair of resilient arms on said back jaw to grip said stud.

5. In a clip brooch, a supporting frame, means 80 for attaching the same to a garment, a clip having front and back jaws with one jaw positioned on one side and the other jaw positioned on the other side of a portion of said frame, snap fastening means between said frame and back jaw to hold the clip and frame assembled comprising a stud on said frame, and a pair of resilient arms 85 on said back jaw to grip said stud, said arms having both ends attached to said back jaw.

6. In a clip brooch, a supporting frame, means 90 for attaching the same to a garment, a clip having front and back jaws with one jaw positioned on one side and the other jaw positioned on the other side of a portion of said frame, snap fastening means between said frame and back jaw to hold the clip and frame assembled comprising a stud on said frame, and a pair of resilient arms 95 on said back jaw to grip said stud, said back jaw being formed of sheet stock and cut out to provide said arms attached at both ends and resilient between said attached ends to grip said stud.

7. In a clip brooch, a supporting frame, means 100 for attaching the same to a garment, a clip having front and back jaws with one jaw positioned on one side and the other jaw positioned on the other side of a portion of said frame, snap fastening means between said frame and back jaw to hold the clip and frame assembled comprising a stud on said frame, and a pair of resilient arms 105 on said back jaw to grip said stud, said back jaw being formed of sheet stock and cut out to provide said arms attached at both ends, said back jaw being generally resilient to 110 grip the stud between said arms.

8. In a clip brooch, a supporting frame, means 115 for attaching the same to a garment, a clip having front and back jaws with one jaw positioned on one side and the other jaw positioned on the other side of a portion of said frame, snap fastening means between said frame and back jaw to hold the clip and frame assembled comprising a stud on said frame, and a pair of resilient arms 120 on said back jaw to grip said stud, said stud being 125 of a long narrow dimension to prevent turning of the clip about the stud as an axis.

9. In a clip brooch, a supporting frame, means 130 for attaching the same to a garment, a clip having front and back jaws with one jaw positioned on one side and the other jaw positioned on the other side of a portion of said frame, snap fastening means between said frame and back jaw to hold the clip and frame in assembled positions, and fingers and a lip on the front jaw to engage 135 one side of the frame for spacing the front jaw from the frame and for locating the clip and the frame in position while the back jaw engages the other side of the frame to locate the back jaw in position relative to the back surface of the frame in the closed position of the brooch.

JULES HIRSCH.
